United States Patent Office

Des. 179,036
Patented Oct. 23, 1956

179,036

CHAIR

Guy G. Rothenstein, Forest Hills, N. Y.

Application April 21, 1953, Serial No. 24,596

Term of patent 3½ years

(Cl. D15—1)

Fig. 1 is a front perspective view of a chair showing my new design, and

Fig. 2 is a side view thereof, slightly in perspective.

I claim:

The ornamental design for a chair, as shown.
